FLUSHING DEVICE FOR WATER-CLOSETS.

1,189,504.

Specification of Letters Patent.

Patented July 4, 1916.

Application filed May 16, 1914. Serial No. 839,078.

To all whom it may concern:

Be it known that I, ROBERT STICKDORN, a subject of the Emperor of Germany, and residing at Gartenstadt Meererbusch, near 5 Osterath, Rhine Province, Germany, have invented certain new and useful Improvements in Flushing Devices for Water-Closets, of which the following is a specification.

10 The present invention refers to a flushing device with air vessel for water closets, in which the inlet valve is opened and placed in connection with the air vessel in known manner by manipulating the operating mechanism, while when the pressure in the 15 air vessel attains a certain value the operating mechanism is automatically actuated by the action of this pressure on a stepped piston in such a manner that when the inlet 20 valve has been closed the air vessel is brought into connection with the flushing pipe. In known devices of this kind the mechanism is operated by hand by pressure on an outwardly projecting part for the 25 purpose of bringing about connection between the flushing pipe and the air vessel, said part being rigidly connected to the operating member. This has the disadvantage that while water is flowing into the air vessel 30 it can be affected by movement of the operating member in the opposite direction so that the air vessel does not become filled to the predetermined extent but the outflow of the water takes place earlier. Such an 35 action on the press button may very naturally be made by a person who is used to the flushing occurring immediately when the valve is operated.

According to the present invention the 40 handle only carries the operating member which is made in the form of a stepped piston by means of a stop, so that the operating of the handle in the opposite direction can have no effect upon it. In this 45 manner the arbitrary operating from outside is rendered impossible when once action has been brought about by the proper manipulation of the stepped piston, so that the action takes place with absolute certainty in the predetermined manner.

50 In the known devices the further disadvantage is attendant on the arrangement of the operating member which is affected by pressure in that the latter has the tendency to sink under the influence of its own weight

so that under certain conditions the outlet valve closes itself and the reservoir is not entirely emptied of water and in fact when the pressure in the pipe sinks temporarily the inlet valve is opened and the flushing 60 can take place. This drawback is removed by the fact that the stepped piston, when in repose, is in its lowest position so that it is kept in repose by its own weight. At the same time the flushing takes place by means 65 of an upward pull.

A further improvement consists therein that the operating mechanism is placed with its axis in a direction which is slanting with regard to the pipe leading to the air 70 pressure vessel. In this manner the water can flow from the air pressure vessel into the flushing pipe which lies in the same line as the stepped piston, without having its direction of flow appreciably diverted and 75 whereby the flushing action is improved in consequence of the small resistance offered to the flow of the water.

The subject of the invention is shown in the drawing in one form of construction. 80

Figure 1 is a section through the operating device and a part of the air vessel. Fig. 2 shows the general arrangement.

The casing *a* containing the operating mechanism has a pipe bracket *b* for the inlet valve *c* and for the attachment of the water supply pipe; said casing *a* is further provided with a pipe bracket *d* leading to the air vessel *e*. The stepped piston *h*, *i* is guided in the casing *a* and is rendered water-tight by sleeves *f* and *g*, the piston *i* having a larger diameter than the piston *h*, the piston being of hollow form. The tubular spindle *l* with a button shaped knob *m* passes into the said piston. The spindle is movably led on the one hand through the restricted portion *k* of the stepped piston situated between the two pistons *h* and *i* and on the other hand through the stuffing box *n*. It is expanded at its inner end at *l* in such a manner that the said expanded end cannot be drawn through the restricted portion of the stepped piston, so that when the button *m* is pulled the piston is drawn from the position shown dotted into the position 100 shown in full lines, while on the other hand when the button *m* is pressed down the stepped piston does not follow this movement.

The main axis of the casing containing 110

the operating mechanism is arranged obliquely with regard to the pipe bracket *d* leading to the air vessel *e*. Consequently the water can, as can be seen from the drawing, flow from the air vessel into the flushing pipe *p* without having its direction of flow greatly deflected, when the stepped piston is in the position shown dotted. The axis of the pipe *b* containing the inlet valve *c* also lies obliquely with regard to the main axis of the casing *a*. The valve *c* has a bearing pin *c*¹ by means of which the opening and closing of the inlet valve is brought about by the action of the piston.

15 The action of the flushing devices is as follows:—When at rest the stepped piston *h*, *i* is in the position shown dotted, so that the casing *a* and the air vessel *e* are entirely free of water, because the channel formed 20 by the restricted portion *k* of the stepped piston places said air vessel and casing in connection with the flushing pipe *p*. If now the stepped piston is brought into the position shown in full lines by pulling the 25 knob *m* then the valve *c* is lifted from its seat *g* by the lifting action of the coned surface *i*¹ which lies between the restriction or inlet *k*, and the piston *i*, on the pin *c*¹, so that water flows from the pipe which is connected to the pipe bracket *b* into the air 30 pressure vessel *e*. The stepped piston is, during this time, secured against movement by the lateral pressure of the water and by the friction against the rubbing surfaces, 35 until a certain pressure has been attained in the air pressure vessel and the pressure in the casing *a* has also risen to such a value that the resistance opposing the movement of the stepped piston is overcome by the 40 excess pressure on the surface of the larger piston *i* and the stepped piston is led into the position shown dotted. By this movement of the stepped piston the valve *c* is at first pressed on to its seat by the pressure 45 of the water acting on it, so that the pin *c*¹ is pushed forward into the restriction or inset *k* of the stepped piston. Only when the valve *c* is entirely closed, does the cylindrical surface of the piston *i* leave the corresponding surrounding surface *r* in the casing, so that the water which has collected 50 in the air pressure vessel now flows through the restriction *k* into the flushing pipe *p*. The stepped piston then remains again in its position until it is again moved upward by the pull of the knob *m*.

55 In consequence of the oblique position of the axis of the inlet valve *c* to the axis of the casing *a*, the coned surface *i*¹ of the piston *i* engages in a particularly favorable manner against the pin *c*¹ of the valve. It can be seen from the drawing, that the axis of the valve is at right angles to the generatrix of this coned surface, so that the 60 component of the movement directed to the

pushing back of the valve coincides exactly with the direction of the axis of the valve.

By adjusting the stuffing-box screw or gland *n*, the downward movement of the stepped piston *h*, *i* can be regulated, in order to be able to adapt the extent of the passage between the lower edge of the surrounding surface *r* and the piston *i* to different water-pressures. At low water-pressure a passage of greater section will be allowed, in order that the water may flow out in a larger stream.

70 The stuffing-box *n* is arranged on a separate part *o*, which is screwed into the casing *a* and which simultaneously serves for 75 clamping in the packing sleeve *f*. The part *o* has a hollow space of such a diameter, that between it and the piston *h* a free annular space *s* remains, the piston *h* being, therefore, guided only at the inner end of 80 the part *o*. If the packing sleeve *f* is not perfectly water-tight, some water escapes into the hollow chamber *s*. In order that it shall not escape from here through the stuffing-box *n* into the open, a hole *t* is provided in the hollow spindle *l*, through which the leakage water can attain the interior 85 of the tube and flow away to the flushing pipe. In this manner any dripping of the leakage water, such as very often occurs in 90 the case of the known devices, is avoided. The interior of the tube *l* is, further, connected with the atmosphere by means of 95 openings *v* arranged under the knob *m*, through which air can be drawn in the 100 event of a suction effect being set up in the casing, for example when the water is drawn off from the house mains, so that any soiling of the water pipes caused by the drawing in of dirty water from the closet is rendered 105 impossible.

As shown in the drawing the air pressure vessel *e* is formed as an annular vessel something like a life-belt, this form presenting the advantage of possessing great strength, 110 so that the air-vessel can be made of comparatively thin material.

Having now described my invention what I claim as new and desire to secure by Letters Patent is:—

115 1. In a flushing device for water-closets the combination of an air vessel, a casing for the operating mechanism, a stepped piston in said casing, said stepped piston being movable into two positions in said casing, an inlet valve in said casing, an inlet water pipe, a flushing pipe, and means to move said piston by hand into one position only whereby the stepped piston is adapted to give free passage from the inlet pipe to the air vessel, said means being slidably mounted in said stepped piston and being provided with a catch in such a manner as to permit its carrying on the stepped piston into the vessel filling position.

tion, while it can return to its idle position independently of the stepped piston.

2. In a flushing device for water closets, the combination of an air vessel, a casing 5 for the operating mechanism, a stepped piston in said casing having two heads and a restriction between the two heads, an inlet valve in said casing, an inlet water pipe, a flushing pipe, said stepped piston giving 10 free passage from the inlet pipe to the air vessel in one position through its restriction, means to move the piston by hand in said position, the inlet valve engaging with the curved surface between the restriction 15 and one head of the stepped piston for actuating the valve by the movement of the stepped piston.

3. In a flushing device for water-closets, the combination of a casing for the operating mechanism, a stepped piston in said casing, said stepped piston being movable 20 into an elevated and a depressed position, an inlet valve in said casing, an inlet water pipe, a flushing pipe, and means for causing 25 a movement of the stepped piston by hand, said stepped piston being hollow and having two piston ends of unequal diameters and having a restricted or inset portion between said piston ends.

4. In a flushing device for water closets, the combination of an air-vessel, a casing 30 for the operating mechanism, a stepped piston in said casing, an inlet valve in said casing, an inlet water pipe, a flushing pipe, 35 and means to move said stepped piston by hand, the axis of said stepped piston being inclined to that of the pipe leading from the casing to the air vessel and being inclined also to the axis of the inlet valve 40 but being in line with the axis of the flushing pipe.

5. In a flushing device for water closets, the combination of an air vessel, a casing 45 for the operating mechanism, a stepped piston in said casing having two piston ends of unequal diameter, an inlet valve in said casing, an inlet water pipe, a flushing pipe, and means to move said stepped piston by hand, the larger piston end being adjacent 50 to the flushing pipe and serving to cut off said flushing pipe from the casing and to open the inlet valve when the stepped piston is moved by hand.

6. In a flushing device for water closets, 55 the combination of an air vessel, a casing for the operating mechanism, a stepped piston in said casing having two piston ends of unequal diameter, an inlet valve in said casing, an inlet water pipe, a flushing pipe, 60 and means to move said stepped piston by hand, said stepped piston having a restricted or inset portion between the piston ends, said restricted or inset portion serving to establish communication between the 65 casing and the flushing pipe and to allow

the inlet valve to be closed by the pressure of the water supply when the stepped piston is automatically returned to its lower position by the excess of pressure bearing on its head of larger diameter.

7. In a flushing device for water closets, an air vessel, an inlet valve, means for actuating the inlet valve by hand to allow of water entering the air vessel, means whereby the air vessel is automatically 70 placed into communication with the flushing pipe when a predetermined pressure is attained in the air vessel, and means whereby the extent of the communicating passage 75 between said air vessel and said flushing pipe may be adjusted to suit the pressure of water available.

8. In a flushing device for water closets, a casing for containing the operating mechanism, means for actuating said operating 85 mechanism, a chamber in said casing for the collection of leakage water and means for conducting said leakage water back into the flushing pipe.

9. In a flushing device for water-closets, 90 in combination, a casing, an air vessel connected thereto, an inlet water pipe and a flushing pipe connected to said casing, a normally closed valve in said casing for controlling the inlet of water thereto, a piston in said casing for closing said flushing pipe normally in open position and out of engagement with said valve but movable into position to close said pipe and to engage and open said valve, the piston being 95 restored to normal position by the water pressure in said casing when the air in said vessel reaches a predetermined pressure.

10. In a flushing device for water-closets, 100 in combination, a casing, an air vessel connected thereto, an inlet water pipe and a flushing pipe connected to said casing, a normally closed valve in said casing for controlling the inlet of water thereto, a piston in said casing for closing said flushing pipe 110 normally in open position and out of engagement with said valve but manually movable into position to close said pipe and to engage and open said valve, the piston being restored to normal position by the 115 water pressure in said casing when the air in said vessel reaches a predetermined pressure.

11. In a flushing device for water-closets, 120 in combination, a casing, an air vessel connected thereto, an inlet water pipe and a flushing pipe connected to said casing, a normally closed valve in said casing for controlling the inlet of water thereto, a piston in said casing having an enlarged portion for closing said flushing pipe normally 125 in open position and out of engagement with said valve but movable into position to close said pipe and to engage and open said valve, the piston being restored to nor- 130

mal position by the water pressure in said casing operating upon said enlarged portion when the air in said vessel reaches a predetermined pressure.

- 5 12. In a flushing device for water-closets, in combination, a casing, an air vessel connected thereto, an inlet water pipe and a flushing pipe connected to said casing, a normally closed valve in said casing for controlling the inlet of water thereto, a piston in said casing for closing said flushing pipe normally in open position and out of engagement with said valve but movable into position to close said pipe and to engage 10 and open said valve, manually movable

means for moving said piston into position to close said pipe and to engage and open said valve, said means being movable independently of said piston in the opposite direction, the piston being restored to normal 20 position by the water pressure in said casing when the air in said vessel reaches a predetermined pressure.

In testimony whereof I have signed my name to this specification in the presence of 25 two subscribing witnesses.

ROBERT STICKDORN.
